Arthur M. Felske, Westport, Conn., assignors to Gen-
eral Electric Company, a corporation of New York

Application September 11, 1956, Serial No. 42,902

Term of patent 14 years

(Cl. D9—2)

Fig. 3.

Fig. 1 is a front elevational view of a vacuum cleaner or similar article embodying our new design.

Fig. 2 is a side elevational view thereof looking in the direction of the arrow in Fig. 1.

Fig. 3 is a perspective view thereof showing the front, top and side opposite to the side shown in Fig. 2.

The back of the vacuum cleaner is the same in appearance as the front, except for the handle and socket escutcheon, which elements appear only on the front.

The dominant features of the design reside in the portion shown in full lines.

We claim:

The ornamental design for a vacuum cleaner or similar article, substantially as shown and described.
